UNITED STATES PATENT OFFICE

WALLACE F. TERRY, OF PITTSBURGH, PENNSYLVANIA, ASSIGNOR TO IRA C. HOUCK,
TRUSTEE FOR H. S. HARROP, F. G. BISHOFF, R. W. WILLIAMS, AND WALLACE F.
TERRY

DESIGN FOR A MARKER FOR AVIATION FIELDS OR THE LIKE

Application filed January 24, 1931. Serial No. 38,441. Term of patent 7 years.

To all whom it may concern:

Be it known that I, WALLACE F. TERRY, a citizen of the United States, and a resident of Pittsburgh, in the county of Allegheny and State of Pennsylvania, have invented a new, original, and ornamental Design for a Marker for Aviation Fields or the like, of which the following is a specification, reference being had to the accompanying drawing, forming part thereof.

Figure 1 is a plan view and Figure 2 is a short edge view, on a reduced scale, of a marker for aviation fields or the like, showing my new design. The marker is intended to be employed in such manner as to be visible from an aeroplane in flight above or near the same, and either portions thereof or the whole may be luminous, or the marker may simply be laid out against a background of different or contrasting color.

The rectangular insertion at the lower left-hand corner of Figure 1 was made to accommodate the name of the inventor and other wording on the drawing.

The complete shape of the dotted-line showing is a true rectangle of the same shape as the figure would be if the lower right-hand lines bounding the figure were extended until they meet each other.

I claim:

The ornamental design for a marker for aviation fields or the like, substantially as shown and described.

In testimony whereof, I have hereunto subscribed my name this 17th day of January, 1931.

WALLACE F. TERRY.

CERTIFICATE OF CORRECTION.

esign No. 87,605.

August 16, 1932.

Wallace F. Terry.

It is hereby certified that error appears in the printed specification of the above numbered patent requiring correction as follows: In the drawing, Fig. 2, should appear as shown below instead of as shown in the patent-

and that the said Letters Patent should be read with this correction therein that the same may conform to the record of the case in the Patent Office.

Signed and sealed this 11th day of October, A.D. 1932.

ea1)

M. J. Moore,
Acting Commissioner of Patents.
